[57] **CLAIM**

The ornamental design for a light stake, as shown and described.

DESCRIPTION

FIG. 1 is a top left front perspective view of the light stake of the present invention;

FIG. 2 is a top right rear perspective view thereof;

FIG. 3 is a top plan view thereof;

FIG. 4 is a bottom view thereof;

FIG. 5 is a front elevational view thereof;

FIG. 6 is a right side elevational view thereof;

FIG. 7 is a rear elevational view thereof;

FIG. 8 is a left side elevational view thereof; and,

FIG. 9 is a fragmentary, environmental front elevational view with the broken line showing of a light being for illustrative purposes and forming no part of the claimed design.

The view of FIG. 9 is shown fragmented for ease and clarity of illustration.
